The ornamental design for a display screen with animated graphical user interface set, as shown and described.

DESCRIPTION

FIG. 1 is a front view of a display screen with animated graphical user interface set showing our new design;

FIG. 2 is the second image thereof;

FIG. 3 is the third image thereof; and,

FIG. 4 is the fourth image thereof.

The appearance of the animated graphical user interface set sequentially transitions between the images shown in FIGS. 1-4. The process or period in which one image transitions to another forms no part of the claimed design. The broken line showing of the display screen, text, and graphic features forms no part of the claimed design.
